UNITED STATES PATENT OFFICE.

HARRY COULSTON, OF PHILADELPHIA, PENNSYLVANIA, ASSIGNOR TO THE PHILADELPHIA TEXTILE MACHINERY COMPANY, OF PHILADELPHIA, PENNSYLVANIA, A CORPORATION OF PENNSYLVANIA.

CONVEYER.

1,022,929.

Specification of Letters Patent.

Patented Apr. 9, 1912.

Application filed August 31, 1911. Serial No. 647,038.

To all whom it may concern:

Be it known that I, HARRY COULSTON, a citizen of the United States, residing in Philadelphia, Pennsylvania, have invented 5 certain improvements in Conveyers, of which the following is a specification.

One object of my invention is to construct a conveyer of the type which will carry flat material and which will allow for the free 10 passage of air to the material.

A further object of the invention is to make a conveyer in such a manner that it can be economically manufactured and readily assembled, and which will be light 15 and strong.

In the accompanying drawings, Figure 1, is a perspective view of a portion of my improved conveyer; Fig. 2, is a transverse sectional view on the line *a—a*, Fig. 3; Fig. 3, 20 is a plan view of a portion of the conveyer; Fig. 4, is a longitudinal sectional view on the line *b—b*, Fig. 3; Fig. 5, is an enlarged longitudinal sectional view illustrating a detail of the invention; Fig. 6, is an enlarged 25 transverse sectional view on the line *c—c*, Fig. 5; Fig. 7, is a detached perspective view of one of the longitudinal bars; and Fig. 8, is a perspective of a modification of the transverse members.

30 While my improved conveyer can be used for conveying materials in general, it is especially adapted for use in machines for drying materials such as veneers, cotton and woolen fibers, tobacco and paper stock, 35 which must be subjected to currents of air while being conveyed. A conveyer of this type usually passes through a suitable chamber in the presence of either heated or cooled air according to the material acted 40 upon.

One of the essential features of the invention is to make the conveyer flat on the carrying surface and this is particularly advantageous in carrying veneers and paper 45 stock in sheets.

The conveyer is made of a series of longitudinal bars 1 bent at each end to form hooks 2, which engage the transverse supporting members 3. These hooked bars are 50 spaced a given distance apart according to the material to be conveyed, as clearly shown in Figs. 1 and 3. The transverse members 3 are carried in the present instance by side chains 4, as indicated in Fig. 2. These side

chains may be of any suitable type made up 55 of links 5 and 6, Fig. 4. The links 5 are specially shaped and are perforated to receive the ends 7 of the transverse members 3 while the links 6 are plane links connecting the links 5. The transverse members 3 are 60 inserted in their respective links and are made of sheet metal bent into the form illustrated in Figs. 5 and 6. The portion 8 is in the form of a tube, and the stiffening web 9 is made in two parts flared as shown in Figs. 65 1 and 5, so as to stiffen the member laterally as well as longitudinally. The web is perforated at intervals directly below the tubular portion 8, as shown at 11. These perforations, in the present instance, are in the 70 form of slots. The hooked ends of the bar 1 pass around the tubular portion 8 and their ends extend through the slots 11. By this construction the bars are held against vertical movement and are held a given distance apart, and yet are free to move longitudinally to a limited extent to accommodate 75 themselves to the movement of the conveyer; especially in passing around the guides at the end of the run.

It will be understood that the longitudinal bars can be spaced at any distance desired and in some cases the bars may not be hooked in every slot in the transverse member when it is desired to make a conveyer in 80 which the bars are located a distance apart, but, as a general rule, the punching of the slots in the cross member defines the spacing of the longitudinal bars.

I preferably make the cross member with 90 the ends flaring as shown in the main figures of the drawing, so as to give the said cross member the lateral strength and stiffness desired, although in some instances, the member may be made as shown in Fig. 8 and 95 the edge of one plate 10 turned up to overlap the other plate. In the present instance, the chains have rollers 12, which travel on guide rails 13 and may be held vertically by a guard rail, while traversing the upper 100 run and at the end of the run the chains pass around the wheels or drums 14. In some instances, where the material is to be held onto the carrying run of the conveyer two conveyers may be placed in such position that the lower run of one conveyer will 105 retain the material, such as a veneer, on the carrying run of the conveyer below it. Dif-

ferent mechanism may be used for imparting motion to the conveyers and the conveyers may be located in any suitable compartments according to the treatment to which the material is to be subjected.

I claim:

1. The combination in a conveyer, of two side chains, a series of transverse supporting members extending from one chain to the other and spaced a given distance apart by the chains, said supporting members having openings therein, with a series of longitudinal carrying members having elongated hooks at each end, said hooks extending around a portion of the transverse members and through openings therein.
2. The combination in a conveyer of a series of transverse supporting members each having a rounded upper section and a perforated web section; with a series of rods

bent at each end to form hooks; the rods resting upon the transverse members and the hooked ends extending through the perforated web section.

3. The combination in a conveyer, of a series of transverse members having perforations, with hooked longitudinal members, carried by the transverse members, the hooks extending through the perforations, the lower portions of the transverse members being flared for the purpose of stiffening said member.

In testimony whereof, I have signed my name to this specification, in the presence of two subscribing witnesses.

HARRY COULSTON.
